Primary Examiner — Janice Patyk*Assistant Examiner* — Ji Sun Yoon(74) *Attorney, Agent, or Firm* — Kunzler Bean & Adamson, PC; Bryan Pitt(57) **CLAIM**

The ornamental design for a cereal dispenser, as shown and described.

DESCRIPTION

FIG. 1 is a top, front and left side perspective view of a cereal dispenser showing my new design;

FIG. 2 is a bottom, rear and left side perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is an exploded perspective view thereof, shown in reduced scale; and,

FIG. 10 is a partially enlarged view thereof, taken from FIG. 2.

The dash broken lines show the portions of the cereal dispenser that form no part of the claimed design. The dot-dash broken lines of FIGS. 2 and 10 are included to show partially enlarged views only and form no part of the claimed design.
